UNITED STATES PATENT OFFICE

2,269,342

INFLATABLE RUBBER GOODS

John H. Johnson, Toronto, Ontario, Canada, assignor to K & W Rubber Corporation, Delaware, Ohio

Application May 31, 1938, Serial No. 210,876

5 Claims. (Cl. 5—350)

The principal objects of the invention are to obviate inherent weaknesses in an inflatable structure such as used in mattresses and cushions or the like and to provide local reinforcements at the points of greatest strain, to thereby prolong the effective life of the structure.

The principal feature of the invention resides in the novel construction and manner of fabricating an inflatable structure of the multi-wall type, whereby a flexible reinforcing agent 10 is incorporated in the zone where the multi-walls are connected by vulcanization.

In the drawing,

Figure 1 is a miniature perspective view partly in section showing a pneumatic mattress constructed in accordance with the present invention.

Figure 2 is a transverse sectional view through the inflatable element of Figure 1.

Figure 3 is an enlarged fragmentary elevation showing a preferred relative arrangement of the component parts of one of the locally reinforced zones.

Figure 4 is a transverse sectional view through the locally reinforced zone after vulcanization and in substantially inflated condition.

Figures 5 and 6 illustrate the present invention applied to the edge construction of an inflatable device.

Figures 7 and 8 show a modified form of reinforced edge connection between respective walls of an inflatable device.

In my earlier United States Patent 1,970,803, granted August 21, 1934, I disclosed an inflatable structure formed from superimposed sheets of rubber separated in certain zones by the interposition of a sheet of paper or the like, so that only the zones not so separated would vulcanize together to form a multiplicity of inter-connected air cells.

It has been found in practice that the greatest strains are localized about the zones which are vulcanized together, resulting in premature deterioration at this point and the present invention has been devised to obviate this inherent objection.

Referring to the drawing, I have shown the present invention applied for purposes of illustration to a pneumatic mattress construction comprising an inflatable element 1 formed of superimposed rubber sheets 2 and 3 which are fabricated in the following manner:

Between the sheets 2 and 3 is placed a separating sheet of paper or other suitable material 4, which is of smaller dimension than the

rubber sheets 2 and 3, to permit the marginal portions thereof to contact, and such paper sheet is provided with openings 5 at a plurality of suitably spaced points which may be representative of the tufting zones 6, and discs 7 and 8 of rubber are placed concentric with the openings 5 on respective sides of the separating sheet 4 as illustrated in Figure 3.

Discs 9 and 10 formed of a suitable strong fabric and of smaller size than the discs 7 and 8, are interposed respectively between said discs of rubber and the outer rubber sheets 2 and 3 and concentrically of the openings 5, and extra reinforcing rings 11 of rubber may, in certain cases, be applied on the outward side of the sheets 2 and 3 to provide a more enhanced thickening in the peripheral zone of the fabric inserts.

When the assembly has thus been effected heat and pressure are applied in a suitable manner and the strata of rubber and fabric in register with the openings 5, as well as the marginal portions of the sheets 2 and 3, will be permanently united and bonded under vulcanizing conditions so that a locally reinforced zone, such as shown in Figure 4, will be produced.

In Figures 5 and 6 the above principle of reinforcement is shown applied to the marginal edge portion of a pair of rubber sheets 12 and 13, the fabric being in the form of a pair of strips 14 and 15, which, as shown in Figure 5, have placed therebetween, a pair of rubber strips 16 and 17 and the separating paper strip 4' extends between the latter for a suitable portion of the width, leaving the remaining portions free to vulcanize together and to permanently bond with the fabric and with the marginal portions of the outer sheets, resulting in an effectively reinforced edge construction as shown in Figure 6.

In Figures 7 and 8 a further modified form of connection is provided between superimposed sheets 12' and 13', in that the fabric reinforcement is shown as comprising a single strip of fabric 18 doubled upon itself and having two strips of rubber 16' and 17' placed therebetween and separated for a substantial portion of their width by the paper-separating strip 4'. This results in a reinforced connection as shown in Figure 8.

It will be understood of course that the fabric may be first treated or coated with rubber compound in any well known manner prior to incorporation in the structure and while I have shown this preferred form of structure incorporating the present invention, the invention is not

to be construed as limited in this regard but broadly resides in the co-operative incorporation of a flexible reinforcing agent where strains originate between two wall portions of an inflatable device subjected to separating stresses.

In Figure 4 the locally reinforced zone is shown perforated at 6' for the passage of tufting cords therethrough, such as when the pneumatic element is provided with a felted covering 1'.

What I claim as my invention is:

1. In an inflatable mattress, paired rubber sheets vulcanized together to form a tufting zone, said zone of vulcanization having incorporated therein a pair of fabric discs spaced apart centrally and extending divergently beyond the zone of connection into said respective sheets, said rubber sheets diverging from the tufting zone and increasing in thickness toward their zone of convergence.

2. In an inflatable rubber device having paired sheets converging to a marginal zone of vulcanization, a strip of fabric doubled upon itself and having its apex portion embodied within said marginal zone of vulcanization and diverging from said zone, and strips of rubber inserted within said doubled diverging fabric strip, the whole being vulcanized together to form an internally reinforced joint.

3. In an inflatable device, a plurality of rubber sheets vulcanized together marginally and at a plurality of local points representative of tufting zones, said rubber sheets diverging from said tufting zones and said tufting zones each

having a pair of spaced apart fabric reinforcement discs internally incorporated therein and diverging therebeyond in a balanced manner in embodied relation to the said diverging portions 5 of said sheets to reinforce the structure against stresses localizing in said zones.

4. In an inflatable rubber device having juxtaposed sheets converging to vulcanized connections in tufting zones, said tufting zones only 10 having spaced apart discs of reinforcing fabric internally incorporated therein and bonded therewith, the edge portions of such spaced discs diverging and extending into said respective juxtaposed sheets and terminating marginally of the 15 tufting zone.

5. In an inflatable rubber device, juxtaposed sheets vulcanized together at a plurality of zones in such manner as to diverge from said zones forming a multiplicity of air cells, and strata 20 of reinforcing fabric incorporated locally in said connected zones and extending therebeyond in diverging paths in embodied relation to said diverging portions of the sheets, the divergent wall portions of said sheets each being of pronounced but gradually increased thickness as 25 they approach the zones of vulcanized connection and said strata of reinforcing fabric terminating marginally within the thickened wall portions adjacent the zones of vulcanization leaving the non-thickened wall portions of the air 30 cells free to normally expand on inflation of the device.

JOHN H. JOHNSON.
